(57) **CLAIM**

The ornamental design for a drill holder, as shown and described.

DESCRIPTION

FIG. 1 is a front view of a drill holder in accordance with the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is an enlarged view of portion 9 of FIG. 1;

FIG. 10 is an enlarged view of portion 10 of FIG. 7;

FIG. 11 is an enlarged view of portion 11 of FIG. 8; and, FIG. 12 shows a drill holder in an environment of use thereof.

The broken lines shown in the drawings represent portions of the drill holder that form no part of the claimed design.

1 Claim, 8 Drawing Sheets
